BROACH

Original Filed Oct. 2, 1961

4 Sheets-Sheet 4

tion is obtained by a pivoted member 55 located to be engaged by a screw located in a work holder and backed up by spring-loaded plunger 56 which is mounted for vertical movement as viewed in FIGURE 1. If a screw blank is located too high in the holder the member 55 is pivoted clockwise about a pivot 57 as viewed in FIGURE 1, to raise the plunger 56 and operate a switch 58 which is connected into the circuit for the drive motor for the machine and which, when operated, stops the motor and operates an indicator light. The second detection control obtained is to determine if a workpiece is properly clamped in the holder. This construction is shown in FIGURE 3 and embodies a member 60 pivoted at 61 and urged toward the work holders by a plunger 62 which is spring-loaded by a spring 63 engaged therewith. As will be seen in FIGURE 3, the member 60 has a first sloped surface 64 and a second sloped surface 65 which, because of the spring loading, delivers a hammer blow to the movable member 43 of the work holder to insure a tight clamped relation with a workpiece. When a movable member is given the hammer blow, the hammer member 60 is in effect driven back, and if the movable member has not moved to clamping position, the hammer member 60 will be driven back too far and the plunger 62 will indicate this position and operate the switch 66 to operate an indicator light which indicates to an operator that a part is not properly clamped and to stop the machine.

Means are associated with the camming device 21 for placing individual workpieces in the individual work holders and as shown this means comprises the feed wheel 31 which is in the form of a disc having a plurality of notches 67 about its periphery each of which can receive an individual screw blank and hold the blank therein whereby as the feed wheel rotates a screw blank in a notch 67 is delivered into a notch 41 of a work holder. Because the screw blank is headed it will seat itself and hold itself within the notches 67 to a work holder notch 41 which is accomplished under the urging of a flexible spring member 68 as assisted by centrifugal force imparted to the workpiece during the rotation of the feed wheel.

Means are provided for driving the feed wheel 31 in timed relation to the work holding drum 21 in order that the feed wheel notches 67 will present themselves in timed relation to the individual work holders. This means comprises a gear 70 rotatable with the drum 21 which meshes with a gear 71 fixed to the shaft 72 to which the feed wheel 31 is loosely mounted. The feed wheel is driven from the shaft 72 by a clutch mechanism embodying a member 73 pinned to the shaft and having a series of pins 74 which are spring loaded upwardly into engagement with the underside of the feed wheel 31 by a spring 75 and engage in recesses on the underside of the feed wheel. If a jam occurs in the feed wheel resulting in inability of the feed wheel to rotate, the clutch pins 74 move out of the recesses on the underside of the feed wheel against the urging of the spring 75 to disengage the drive to the feed wheel. This disengagement results in operation of a switch 80 shown in FIGURES 1, 2 and 3, which switch is actuated through a motion transmitting cable 81 to operate an indicator light and stop the machine.

One additional limit switch is provided to detect the failure of a part to drop out of the work holder after broaching, with this switch being indicated at 85 in FIGURE 1 and including a pivotal feeler 86 positioned to be engaged by a part remaining in the work holding drum 21 to shift contact with the switch to stop the drive motor and operate an indicator light in the event a part remains in the drum.

The feed wheel 31 and parts associated therewith are mounted on and within a housing 87 which is supported from the frame of the machine by an arm 88.

The broaching tool is shown in FIGURES 12-14 and embodies a generally flat blade-shaped body 90 with a

series of teeth 91 along one edge thereof arranged to define a curved cutting profile with the specific form being shown as an arc of a circle. The body of the blade is shaped to have a rear edge 92 and a trailing side edge 93 arranged at an acute angle of approximately 60° and with the trailing side edge 93 being generally parallel to a face 94 of a cutting tooth. The back edge 92 of the blade body is generally parallel to a tangent of the curved cutting profile intermediate its ends. As shown, the teeth have a positive rake angle and have a form whereby the tooth is identical after sharpening, and also the location of the teeth is maintained identically relative to broach holder locating surfaces subsequently to be described.

Each of the broaching stations 23 and 24 is basically the same, with the second station being used only to provide a depth of cut in a workpiece greater than that provided by the first station.

Each of the broach holders 23 and 24 is similar, and the broach holder 23 will be described in detail. The broach holder embodies a frame 100 with a plate 101 against which the broach 90 rests, and the broach is held within the holder by a quick release mechanism embodying an arm 102 which is pivoted at 103 to a member 104 swivelly mounted in the frame 100. The opposite end of the arm 102 has an open ended slot 105 which fits an undercut part of a pin 106 secured in the frame 100. The arm 102 carries a pair of threaded members 107 and 108, each of which has pressure pads 109 which engage the opposite face of the broach body 90. With the parts in assembled relation as shown in FIGURES 4 and 5, the turning of the members 107 and 108 causes the pads to firmly engage the broach and to hold the arm 102 in broach clamping position. When it is desired to change a broach, the members 107 and 108 are backed off, which then frees the arm 102 for rotation about the swivel 104 until the notch 105 is released from the pin 106 and then the arm 102 may be swung about the pivot 103 to move the arm out of the way for access to the broach.

The broach in effect is held in a slot with a bottom or left-hand side of the slot as viewed in FIGURE 4 being defined by a bar 110 carried on a base 111 which is adjustably mounted on the frame 100 by means of a central key 112. The adjustment of the base 111 relative to the frame 100 is obtained by the threaded member 113, and the position is maintained by a pair of tightening bolts 114 and 115 which pass through slots in the base 111 and attach to the frame 100. The key 112 is arranged at an angle of 15° to a radian from the axis of rotation 22 for the work holding drum 21. The thrust of the broaching action is taken by a member 120 having a flat surface to engage the side edge 93 of the broach tool, and this member can rotate to maintain its contact with the edge of the broach tool even though the inclination of the broach may be varied as subsequently described. The member 110 against which the rear edge 92 of the broach engages, in addition to being movable with the holder base 111, is mounted for pivotal movement about a pivot pin 125 which is on a radial line of the work holding drum axis 22 which also passes through the last tooth 91 of the broach tool. This angular adjustment permits tilting of the tool to determine the rise per tooth and with the relation along the radial line, permits this while maintaining the setting of the last tooth for final depth of cut. The angular adjustment of the member 110 is accomplished by rotation of a pin 126 having an eccentric surface 127 engageable with the member 110. The adjustment movement is permitted by loosening of a tightening bolt 128 passing through an oversize opening in the member 110, which is of a size to avoid any interference with the angular adjustment, and when the tightening bolt is tightened 75 the member 110 is held in an adjusted position.

As stated previously, the broach holder at broach station 24 is the same as the holder at station 23 and similar reference numerals have been applied thereto.

We claim:

1. In a rotary broaching machine, a broach having a blade-shaped body with a plurality of teeth arranged to define a curved cutting profile as an arc of a circle, said body having a back edge generally parallel to a tangent of said circle and a side edge at an angle of approximately 60 degrees to the back edge and generally parallel to the faces of the cutting teeth.

2. In a rotary broaching machine, a broach having a blade-shaped body with a plurality of teeth arranged to define a curved cutting profile as an arc of a circle, said body having a back edge generally parallel to a tangent of said circle and a side edge at an acute angle to the back edge and generally parallel to the faces of the cutting teeth.

3. A broach having a flat blade-shaped body with a plurality of teeth along one edge thereof with each tooth having a face extending inwardly from the cutting edge of the tooth and defining a positive rake angle with respect to a workpiece path, said body having a back edge opposite to said one edge, a trailing side edge connecting said one edge and the back edge extending at an acute angle to said back edge and generally parallel to the face of the tooth adjacent said side edge whereby the tooth form and location remains in a constant relation to said side edge after each sharpening of the broach.

4. A broach as defined in claim 3 in which a remaining side edge of said body is at a distance from the nearest tooth to provide sufficient body material for repeated sharpenings as said nearest tooth progressively approaches said back edge.

5. A broach having a generally planar body of a trapezoidal configuration with generally parallel side edges one of which trails the other with respect to a workpiece path, a back edge extending between said side edges and a row of cutting teeth extending along the remaining edge, the trailing one of said side edges and

the back edge intersecting at an acute angle to each other with the resultant force from cutting directed generally toward said intersection, one of said teeth adjacent said one side edge having a face extending inwardly from said remaining edge generally parallel to said trailing one side edge and defining a positive rake angle with respect to said workpiece path, whereby said one tooth remains in known relation to said intersection after repeated sharpening of the broach.

10 6. A broach having a generally planar body of a trapezoidal configuration with generally parallel side edges, a back edge extending between said side edges and a row of cutting teeth extending along the remaining edge, one of said side edges and the back edge intersecting at an acute angle to each other with the resultant force from cutting directed generally toward said intersection, one of said teeth adjacent said one side edge having a face extending generally parallel to said one side edge whereby said one tooth remains in known relation to said intersection after repeated sharpening of the broach, each of said cutting teeth lying on an arc 15 of a circle with said back edge extending generally parallel to a line tangent with a tooth located generally midway between the ends of said row of teeth.
